UNITED STATES PATENT OFFICE.

HANNAH R. JOHNSON, OF BRADDOCK, NORTH DAKOTA.

CLOTHES-LINE AND DETACHABLE SUPPORT.

SPECIFICATION forming part of Letters Patent No. 693,401, dated February 18, 1902.

Application filed October 5, 1901. Serial No. 77,655. (No model.)

To all whom it may concern:

Be it known that I, HANNAH R. JOHNSON, a citizen of the United States, residing at Brad- dock, in the county of Emmons and State of 5 North Dakota, have invented certain new and useful Improvements in Clothes-Lines and Detachable Supports; and I do hereby declare the following to be a full, clear, and exact description of the invention, such as will enable 10 others skilled in the art to which it appertains to make and use the same.

My invention has for its object to provide a simple and efficient device whereby clothes may be detachably secured to a line without 15 being directly applied thereto, all as herein-after more clearly set forth; and to the above end the invention consists of the novel devices and combinations of devices hereinafter described, and defined in the claims.

20 It is a well-known fact that in the winter-time when clothes are hung on a line and secured by pins in the ordinary way they become frozen to the line, so that they are removed with difficulty and are very frequently torn. Furthermore, when applied directly to the line the clothes are subjected to great wear under the flapping action of the wind, which keeps the clothes rubbing the said line. Also 25 it is evident that in very cold weather both 30 the operations of hanging the clothes out and removing the same from the line are disagreeable jobs which it is desirable to accomplish as rapidly as possible.

In accordance with my invention I provide 35 in connection with a line of suitable construction a plurality of detachable clothes-supporting brackets. These clothes-supporting brackets are provided with hooks for detachably securing them to the line and with trans- 40 versely-extended sections to which, by means of ordinary clothes-pins, the clothes may be secured within doors and afterward secured to the line by the said devices.

My invention is illustrated in the accom- 45 panying drawings, wherein like characters indicate like parts throughout both views.

Figure 1 is an elevation showing several pieces of clothes or apparel suspended from a line by devices constructed in accordance 50 with my invention, and Fig. 2 is an enlarged view of certain of the parts shown in Fig. 1.

The numeral 1 indicates a post or clothes-line support, shown as provided with a screw-eye 2, to which is attached one end of a twisted wire clothes-line.

55

At suitable intervals the line 3 is formed with eyes or loops 4. The numeral 5 indicates articles of wearing-apparel. The numeral 6 indicates ordinary clothes-pins.

My improved supporting-brackets are pref- 60 erably constructed as shown in the drawings, being made from a single piece of wire bent to form hooks 7 and pronged lower ends 8, connected by transverse portions 9. The clothes are adapted to be folded over the transverse 65 portions 9 and to be secured thereto by the clothes-pins 6. The transverse bar portion 9 is connected at its ends to the lower ends of the prongs 8 by depending loop-sections 10, into which the upper but downward-turned 70 edges of the clothes may be turned when the devices are applied thereto, as shown in the drawings. The hooks 7 adapt the supporting-brackets to be quickly and detachably secured to the eyes or loops 4 of the line 3. 75

With these supporting-brackets the clothes may be quickly removed from the line, and the brackets themselves may be removed from the clothes at leisure and at any time after the clothes have been carried into the house 80 and thawed out. It is also evident that these supporting-brackets may be secured to the clothes before they are removed from the house, in which case they may, by means of the said brackets, be quickly strung upon the 85 line. These supporting-brackets with hooked ends are capable of use in connection with any kind of a line; but the clothes are more satisfactorily held in place when the said brackets are used in connection with a line 90 such as described, which is provided at intervals with eyes or loops. If in the summer-time the detachable brackets are not deemed necessary, the line 3 may be used in the ordinary manner, inasmuch as the loops or eyes 4 95 will not prevent the application of ordinary clothes-pins. The supporting-brackets them- selves are also capable of considerable modi- fication within the scope of my invention.

What I claim, and desire to secure by Let- 100 ters Patent of the United States, is as follows:

1. A detachable clothes-support formed

from a single piece of wire bent to afford the hook 7, diverging arms 8, transverse section 9 and depending loops 10.

2. The combination with a clothes-line having loops or eyes at intervals, of a plurality of detachable clothes-supporting brackets, each of which brackets has a hook for detachably securing the same to the eyes or loops of said line and is provided with a transverse

portion to which the clothes are adapted to be pinned, substantially as described.

In testimony whereof I affix my signature in presence of two witnesses.

HANNAH R. JOHNSON.
